UNITED STATES PATENT OFFICE.

EZRA KAPLAN, OF CHICAGO, ILLINOIS, ASSIGNOR TO NATIONAL ART NOVELTY COMPANY, OF CHICAGO, ILLINOIS, A CORPORATION OF ILLINOIS.

HANGER FOR PICTURES AND THE LIKE.

1,248,131.

Specification of Letters Patent.

REISSUED
Patented Nov. 27, 1917.

Application filed January 24, 1917. Serial No. 144,192.

To all whom it may concern:

Be it known that I, EZRA KAPLAN, a citizen of the United States, residing in Chicago, in the county of Cook and State of Illinois, have invented a certain new and useful Improvement in Hangers for Pictures and the like, of which the following is a full, clear, concise, and exact description, reference being had to the accompanying drawings, forming a part of this specification.

My invention relates to hangers such as are employed for hanging small pictures, calendars and the like. The object of the invention is to provide improved and simplified means for hanging small picture frames and the like.

In the accompanying drawings I have illustrated one embodiment of my invention.

Figure 1 is an elevational view on an enlarged scale of the metal hanger;

Fig. 2 is an elevation of the rear of the card or mounting to which the hanger is attached;

Fig. 3 is a front view of the card or mounting with the hanger attached; and

Fig. 4 is a cross sectional view showing the manner of attaching the hanger to the mounting card or board.

In preparing small pictures, calendars and the like which are adapted to be hung upon a supporting nail or the like, it is desirable to provide a hanger which may be easily applied to the article to be hung which will be permanent when in place and which will be relatively inexpensive to manufacture and to apply.

I provide a sheet metal stamping of the form shown in Fig. 1 having an eye portion 1 attached to a shank portion 2, this shank portion having a tongue or spear 3 struck or slotted out of the main shank portion 2. The manner of forming the tongue 3 is such that the base of the tongue 3 lies at the base 45 of the shank 2, and both the tongue and the shank point in the same direction. At the junction of the shank portion with the eye of the hanger I provide a pair of shoulders 4 for preventing movement of the hanger 50 after the same is in place on the mounting card.

The mounting card or back 5 is provided at a suitable point preferably near its upper end with a slot 6 of substantially the width 55 of the shank portion 2. The hanger is ap-

plied to the mounting card or board 5 by pushing the shank 2 together with the tongue or spear 3 through the slot until the shoulders 4 rest against the back surface of the mounting card. The main part of the shank 2 is then bent upward, as is shown in Figs. 3 and 4 and the tongue or spear 3 is bent down. The mounting card 5 is then covered with a suitable card, picture or the like, as is shown in dotted lines at 7 and a binding or frame 8 may be applied to the edges to hold these parts in place.

It is apparent that the hanger is solidly secured in place as the same can not pull outward without straightening the parts 2 and 3 and cannot be pushed inward because of the shoulders 4. Movement upward is prevented by the shank 2 which supports the weight of the mounting card 5 and attached parts and movement downward is impossible because of the tongue or spear 3. I wish to call particular attention to the fact that the main part of the shank 2 is bent upwardly and the tongue or spear 3 being bent downwardly. Thus, not only is the material placed to the best advantage with regard to strength, but an important advantage is secured in attaching the device. It would be very difficult to bend the tongue or spear 3 upwardly without bending the main shank 2, but it is relatively very easy to bend the main shank 2 upward as is shown without touching the spear 3 and thus attachment of the hanger may be quickly and easily made.

I do not wish to be limited to the precise details of construction shown and described.

I claim:

1. A hanger comprising a flat piece of sheet metal having an open eye member at one end, a flat shank member of substantially uniform width for the major part of its length integral with the eye member and forming the opposite end, shoulders extending laterally from the hanger at the upper end of the shank member, said shoulders and eye member being adapted to lie on one side of a card and a tongue pointing in the same direction as the shank member, said tongue being struck out of the shank member by a U-shaped cut, the base of the tongue lying substantially at the base of the shank, said tongue and shank being adapted to be passed through a slot in the card to the opposite side and be bent in different directions.

2. In a device of the class described, an eye portion and a shank portion having a tongue struck up from said shank portion, the base of the tongue lying at the base of 5 the shank, said tongue and shank extending in the same direction, said shank portion being adapted to be bent back substantially parallel with and overlying the eye portion with said tongue extending downward 10 substantially in line with the eye portion, said eye portion being adapted to lie on one side of the card, the shank and tongue portion being adapted to lie on the other side.
3. A hanger comprising an eye portion, a 15 shank portion integral with said eye portion, a tongue struck up from said shank portion, the base of the tongue lying at the base of the shank, said tongue and shank extending in the same direction, said shank being 20 adapted to be bent back substantially parallel with the eye portion, and a shoulder projecting from the side of the hanger to limit the inward movement of the hanger.
4. In combination a mounting card having 25 a slot therethrough, a hanger having a shank projecting through said slot and lying against the back surface of said card

above the slot, a tongue integral with and struck up from the body of said shank, said tongue lying against the back surface of the 30 card below the slot, and an eye portion above said shank and attached thereto, the base of the tongue lying at the base of the shank, said tongue and shank extending in the 35 same direction.

5. In combination a mounting card having a slot therethrough, a hanger comprising an eye portion and a shank portion integral therewith, shoulders projecting from the side of said hanger and engaging the 40 card to limit movement of the hanger through the slot, and a tongue struck up from the shank portion, said shank projecting through said slot, said main part of the shank being bent upwardly and the tongue 45 being bent downwardly both upon the side of the sheet opposite the eye portion, the base of the tongue lying at the base of the shank, said tongue and shank extending in the 50 same direction.

In witness whereof, I hereunto subscribe my name this 20th day of January, A. D. 1917.

EZRA KAPLAN.
